ENDGATE.

Charles R. Adams, Donavon, Saskatchewan;
CanadaApplication October 20, 1945, Serial No. 623,564;
In Canada March 8, 1943

4 Claims. (Cl. 296—50)

1

This application constitutes a continuation-in-part of my United States Patent application Serial No. 480,517, filed on the 25th day of March, 1943, now abandoned, and my invention relates to improvements in end-gates, for vehicles, particularly grain wagons, grain trucks and the like, a principal object of the invention being to provide a device of the character herewithin described which is leak-proof, thereby preventing the loss of grain from the wagon or truck while in transit to the elevator.

A further object of my invention is to provide a device of the character herewithin described which is pivoted adjacent one of the lower corners thereof for vertical movement in its own plane, and normally bounded by a leak-proof slot on three sides thereof.

A further object of my invention is to provide a device of the character herewithin described which may readily be installed in any existing grain wagon or truck in a minimum of time and with ease.

A further object of my invention is to provide a device of the character herewithin described which is of eminently simple and rugged construction, easy to raise and to detach bodily from a vehicle.

With the above more important objects in view and such other minor objects as may appear as the specification proceeds, my invention consists essentially in the arrangement and construction of parts all as hereinafter more particularly described, reference being had to the accompanying drawings, in which—

Figure 1 is a rear elevation of my end-gate and associated assembly showing the left hand lower corner structure thereof, enlarged.

Figure 2 is a perspective detail of my device and illustrating the angulation of my end-gate slot as seen from above.

Figure 3 is a section on the line 3—3 of Figure 1.

Figure 4 is a perspective detail illustrating a part of my invention as viewed from below.

Figure 5 is an illustration similar to Figure 1 of an alternative embodiment of my grain door.

Figure 6 is a plan view of the alternative embodiment of Figure 5.

Figure 7 is an enlarged view of the left end of Figure 6 showing my door in the plane of the vehicle rear-end in full lines.

In the drawings like characters of reference indicate corresponding parts in the different figures.

2

Referring first to the embodiment of my invention illustrated in Figures 1 to 4 inclusive, it is to be seen that I make use of strips of metal flat stock 1 and 2, the strip 1 being in the order of 4 to 6 inches wide and one-eighth of an inch thick while the member 2 is preferably approximately 1 inch wide but three-eighths of an inch thick.

The strip 1 is secured to the upper surface of the rear transverse edge of the floor 3, and projects somewhat beyond the extreme edge as clearly illustrated in Figures 2, 3 and 4. At the side edges of the floor, the strip is angled into the vertical, the vertical portion thereof being enumerated 4, and being secured as best illustrated in the accompanying Figure 3 to the inner face of the rearmost stakes 5. As clearly illustrated in Figure 2, the vertical portions 4 overlap the rearmost portions of the side walls 6 and may be continued upwardly to any height desired.

The strip 2 is positioned beyond the rear edge of the floor 3, but extends parallel with the strip 1, being spaced therefrom to provide the horizontal slot 7 which receives the lower horizontal edge 8 of my end-gate 9. The strip 2 is supported on the bracket 10, and it will be noted that one end 11 of the strips projects outwardly beyond the boundaries of the wagon or truck body for a reason presently to be described.

Secured as by welding or by means of bolts to the upper surface of the strip 2, and parallel and in alignment with the portions 4, are strips or vertical portions 11 of the same width as the strip 2, but preferably of lighter gauge although this is not necessary, and, if desired, the strips or portions 11 may be formed of the same stock as the strip 2, in which case the extension 11 may be attached as by welding.

The strips 11, being spaced from the portions 4 to a similar extent as the strip 2 is spaced from the strip 1, vertical slots 12 are provided to receive the side edges 13 of my end-gate 9. In conclusion, in this context, it is to be noted that all the strips hereinbefore referred to lie in a manner which I define as "flatwise," by which I mean that the wider surfaces, as opposed to the edges thereof, lie in the plane of the walls and floor of the vehicle body, so that considerable stiffness exists against distortion under the influence of horizontally applied gate-pressure. The edges of the strip will also lie straighter and preserve truer parallelism than would be the case if the wide surfaces of the aforesaid strip were normal to the vehicle body wall and floor plane, which surfaces

would be liable to "wave" slightly, or, as a result of rough usage, become substantially distorted.

The end-gate itself is provided at one of the lower corners thereof with a projecting handle 14 rotating the same vertically in its own plane as indicated by the arrow 15, while the opposite lower corner is provided with the projection or extension 16 (shown magnified as to size in comparison with the rest of Figure 1). Upon the extension 16 is a bolt or stud 17 designed to extend through the slot 18 formed upon the vertical flange 19 of a piece of angle iron 20, the horizontal flange 21 of which is secured, as by welding to the upper surface of the projecting portion 11 of the strip 2.

By reference to the magnified left hand lower portion of the accompanying Figure 1, it will be seen that my slot 18 is angulated vertically as at 22, being open at the angulated end thereof so as to permit removal of the stud 17 when the gate is pushed to the right, and then raised by the application of an upwardly directed force upon the projection 16.

However, I wish it to be noted particularly that, as I have indicated by means of dotted lines 23, the slot 18 is recessed at the closed end thereof so as to provide a semi-circular seating for the stud thus preventing the gate from sliding downwardly and to the left when raised via the handle 14.

From the foregoing it will be clearly understood that the side edges 13 and the lower horizontal edge 8 are snugly positioned between the slots 12 and the slot 7 respectively when in closed position, hence no leakage can occur as is the case with the conventional end-gate.

I would draw attention to the swinging bridge-piece 24 which hangs upon a stud secured to the inner surface of the portion 4 remote from the hinged or pivoted side of my gate. This bridge-piece is provided with the slot 26, and may therefore be moved endwise to a limited extent or rotated so as to span the upper portion of the adjacent slot 12 and rest upon the lug 27 projecting inwardly in the same horizontal plane from the adjacent strip 11. By means of this simple expedient, I am able to maintain my gate in the raised position for the discharge of grain. In this context also, it is to be noted that the pivoting of my gate for vertical movement in its own plane at a point beyond the adjacent side edge 13, or in other words, beyond the boundary of the grain enclosing box, provides an opening the full width of the box for the discharge of grain when the door is raised. Thus, grain cannot collect in one of the rear corners of the box necessitating its removal as by shovelling.

In the embodiment of Figures 5 to 7 inclusive I would explain that my gate 28 is substantially similar to the gate 9 of my first embodiment except that instead of being provided with a stud 17, I simply provide an aperture 29 in the extension 30 thereof, a strip of angle iron 31 upon the upper edge to facilitate lifting, and an aperture 32 in the handle 33 through which a bar or the like may be passed to aid in securing an upward purchase for the purpose of "starting" the gate, particularly when bulk materials like gravel are being hauled, and which have a very high coefficient of friction against the inner surface 70 of the gate.

It is also to be understood in connection with this alternative embodiment of my invention which I am now describing that I provide a strip 34 upon the inner surfaces of the rear-end of the

vehicle box 35, in all respects similar to strip 1, the strip 36 including the vertical portion 37 being also similar to strip 2 including the right hand vertical portion 11. Upon the left hand side, with respect to the accompanying figures however, it will be observed that the vertical strip portion 38 is slightly misaligned with respect to the vertical portion 39 of strip 34, or in other words, is offset leftwardly with respect thereto, towards stud 40.

Upon the projecting left end portion 41 of the strip 36 is secured a piece of angle iron 42, the same comprising with the portion 41 what I define as a horizontal extension, and through 15 said extension and protruding horizontally therefrom upon the front surface thereof is a stud 43, the same being rigidly secured in the position described. My gate 28 is mounted upon this stud, and rotates vertically thereabout as indicated by arrow 44.

It is to be understood that as in my first embodiment, the adjacent parallel edges 45 and 46 will only be spaced apart by a distance a few thousandths of an inch more than the thickness 25 of my door. However, in this embodiment I have devised what I conceive to be improved and simplified means for removing my door bodily and eliminating the necessity for limited transverse movement in the plane which it occupies between 30 strips 34 and 36, etc., as is necessary in my first embodiment.

To this end, it is to be understood that after elevating my door into the inclined position of Figure 5, but to the greater extent than shown 35 which is necessary for freeing the right end from portion 37, I am able to rotate the same through a substantially horizontal path as per the arrow 47 of Figure 6, and only then do I withdraw the gate by movement in its own plane 40 as indicated by arrow 48, and after the frictional engagement thereof with material remaining in the box has been relieved.

The reason for the offsetting of the portions 38 and 39 will now be apparent, because, by this expedient 45 I am able to maintain a spacing between the adjacent surfaces of the portions 38 and 39 equal to that of the edges 45 and 46, while at the same time permitting a greater diagonal space (indicated by the double-headed arrow 49) between the adjacent edges of the members 38 and 39. By the provision of a greater distance between such edges, I am able to avoid pinching of my gate between the members 38 and 39 during the oblique or skewed withdrawal thereof.

After my gate has been dismounted from stud 43, it will be understood that it will fulcrum during the horizontal travel as per arrow 47, on the member 38 adjacent the right hand end of the horizontal projection 30. Accordingly, I consider it advisable in this embodiment to secure the portion 38 to the portion 36 as by means of welding or the like, rather than by riveting as in the first embodiment of my invention illustrated in Figure 1, although obviously, this is not of critical importance.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this in-

vention may be made within the scope of the accompanying claims without departing from the spirit and scope of the same it is intended that all matter contained in the accompanying specification shall be interpreted as illustrative only and not in a limiting sense and I desire only such limitations placed thereon as justice dictates.

What I claim as my invention is:

1. In combination a vehicle end-gate vertically rotatable in its own plane, said end-gate being characterised by the provision of horizontal projections at the lower corners thereof, and structure for rotatable attachment of said end-gate aforesaid, and for the removal thereof, consisting of a horizontally projecting stud on one of said projections, a projecting support extending parallel with the said projection to which said stud is secured, said support being horizontally slotted to receive said stud, said slot angulating vertically, and being open at the vertically angulated end thereof to permit removal of said stud.

2. In combination with a vehicle end-gate, a pair of parallel strips of rigid material extending flatwise and horizontally across said vehicle at the rear end thereof, said strips being spaced to provide a leak proof slot to receive the lower edge of said gate, said strips being angulated into the vertical adjacent the longitudinal edges of the floor of said vehicle and providing vertical leak proof slots adjacent the side walls of said vehicle body to receive the side edges of said gate, and means for securing said end-gate for vertical rotation in its own plane, and for ready removal from said vehicle body which consists of a projecting stud secured to said end-gate in the vicinity of one of the lower corners thereof, and a horizontally slotted support, the slot in said support angulating vertically and being open at the upwardly angulated end to permit insertion and removal of said stud.

3. In combination, a vehicle end-gate having a horizontal projection in its own plane at one of the lower corners thereof, metallic stripping structured to provide a continuous slot for the side edges and the under-edge of said gate, se-

cured to the body of said vehicle along the rear edges of the floor and side walls thereof, a horizontal extension projecting from said metallic stripping in the vicinity of one of the lower rear corners of said vehicle body and in a plane parallel to that of said gate and said horizontal projection, said horizontal projection being pivotally connected to said extension to allow rotation of said gate thereabout in its own plane.

4. In combination, a vehicle end-gate having a horizontal projection in its own plane at one of the lower corners thereof, metallic stripping structured to provide a slot for the side edges of said gate, secured to the body of said vehicle along the rear edges of the side walls thereof, a horizontal extension projecting from said metallic stripping in the vicinity of one of the lower rear corners of said vehicle body and in a plane parallel to that of said gate and said horizontal projection, a stud secured to and projecting from said extension, said horizontal projection being mounted on said stud to allow rotation of said gate thereabout in its own plane, said metallic stripping including a vertical portion secured to the vertical rear edge of the side wall of said vehicle which is adjacent said extension, and a second portion parallel with, and spaced from the first portion, said second portion being offset from the first portion towards said stud to permit partial rotation of said gate through a plane normal to that of the gate itself following the inclination thereof about said stud prior to the dismounting of said gate from said stud, and prior to removal of said gate from said vehicle.
